Primary Examiner — Barbara Fox*Assistant Examiner* — Lilyana Bekic(74) *Attorney, Agent, or Firm* — Condo Roccia Koptiw LLP(57) **CLAIM**

The ornamental design for an inhaler cap, as shown and described.

DESCRIPTION

FIG. 1 is a top front perspective view of an inhaler cap attached to an inhaler, showing my new design;

FIG. 2 is a bottom front perspective view of the inhaler cap shown in FIG. 1, with the inhaler removed;

FIG. 3 is a back side plan view of the inhaler cap shown in FIG. 1,

FIG. 4 is a top view of the inhaler cap of FIG. 1; and,
FIG. 5 is a bottom view of the inhaler cap of FIG. 1.

The broken lines illustrating the inhaler in FIG. 1 illustrates the environment and forms no part of the claimed design. All other broken lines in the drawings illustrate portions of the inhaler cap that form no part of the claimed design.
